CROP DUSTING EQUIPMENT

Stanley Hiller, Jr., Menlo Park, and Robert A. Wagner, Playa Del Ray, Calif., assignors to Hiller Helicopters, San Mateo County, Calif., a corporation of California

Application May 1, 1950, Serial No. 159,294

4 Claims. (Cl. 43—148)

1

This invention relates to crop dusting equipment, and more particularly to such equipment adapted for use on aircraft.

The employment of crop dusting equipment on aircraft, especially rotary wing aircraft such as, 5 helicopters, is becoming quite prevalent. One of the problems encountered in uniformly distributing the dusting material, which may be any suitable fungicidal or insecticidal chemical material well known in the industry, is that of obtaining a fine powdered dispersal or spray of the material so that it may efficiently cover the areas to be sprayed without waste. It is sometimes difficult to obtain this result because of the tendency for the material to cake particularly when it is moist or damp. Also, the usual speed of the aircraft presents a problem in obtaining uniform dusting in a fine powder.

The present invention has for its objects, among others, the provision of improved dusting equipment of the character related, which will entirely obviate caking of the material to be dusted, which will effect uniform dusting, and which is of relatively simple, light weight, and economical construction. Summarizing the invention, an important feature thereof resides in the provision of a special baffle arrangement in a generally horizontally extending blast tube which communicates with the bottom of an upright hopper structure for the dusting material. Such tube is adapted to receive a blast of air adjacent one end thereof and to discharge the material from the opposite end.

The material is fed from the hopper structure into the blast tube; and to prevent caking of the material which may otherwise result in clogging of the blast tube, a plurality of vertically spaced generally horizontally positioned baffles is provided in the tube underneath the hopper structure, with adjacent ends of the baffles in spaced overlapping relationship. The uppermost baffle is adjacent the blast receiving end of the tube while the lowermost baffle is adjacent the discharge end of the tube.

Suitable means is provided in the hopper structure for agitating the material therein to minimize caking, and also to feed regulated predetermined quantities of the material into the blast tube, so that it will not become overloaded and thereby become clogged. Also, vibrators are provided on the hopper structure to aid in preventing caking of the material.

A preferred embodiment of the invention is illustrated in the drawings in association with a rotary wing aircraft, such as a helicopter,

2

where the equipment has found great applicability. It is to be understood, however, that the equipment may be employed with any other type of aircraft.

In the drawing:

Fig. 1 is a schematic perspective view of a portion of the body of a well known type of helicopter on which are mounted two crop dusting units of the invention;

10 Fig. 2 is a vertical longitudinal sectional view through one of the equipment units; certain parts shown in Fig. 1 being omitted and broken away to shorten the view; and

Fig. 3 is a transverse vertical section taken 15 in a plane indicated by line 3—3 in Fig. 2.

With reference to Fig. 1, the helicopter body 2 is provided with the usual upright cooling fan 3 for the engine (not shown) and with the usual fan housing 4. For crop dusting work, a crop

20 dusting equipment unit 5 is detachably mounted at each side of the helicopter by any suitable means including bracket structure 6 and a support hook 7 (Fig. 3) adapted to be detachably connected to the body of the ship. Each unit 25 comprises a generally horizontally extending blast tube 8 having a top opening communicating with the bottom of an upright hopper structure 9. The hopper structure includes an upper funnel shaped hopper housing 11 having a flanged 30 connection 11' with a feed valve housing 12 located between the bottom of hopper housing 11 and the top of the blast tube 8.

The air inlet end 13 of blast tube 8 is connected by means of suitable piping 14 and adaptor 16 35 to fan housing 4, so that the blast tube receives a continual blast of air as long as the engine is running. As indicated in Fig. 1, the opposite end of the blast tube is connected to a tail pipe 17 from which the dusting material is dispersed over the ground in the form of a fine powder or spray resulting from the blast of air.

An important constructional feature in the blast tube, which prevents caking of the material to insure that it is dispersed in the form of a fine powder, is the provision of a plurality of horizontally positioned baffles 18 underneath the hopper structure and between air inlet end 13 and the discharge end adjacent tail pipe 17. Baffles 18 are in the form of plates which extend the width of the blast tube, and are provided with suitable side flanges 19 secured against the inner sides of the blast tube.

They are vertically spaced or in other words arranged in stepped relationship, with their adjacent ends in spaced overlapping relationship,

3

so that an opening 21 is provided between adjacent ends of the baffles through which the blast of air may pass. The uppermost baffle is adjacent the blast receiving end 13 of the blast tube while the lowermost baffle is adjacent the discharge end of the tube. By the described arrangement, all the material discharged from the hopper structure 8 into the blast tube is thoroughly aerated; and any tendency of the material to cake is entirely obviated.

A rotary feed valve 22 is provided in the feed valve housing 12 to measure predetermined regulated quantities of material into the blast tube; the feed valve being mounted for rotation with a shaft 23 projecting through, and journalled in opposite walls of the feed valve housing by means of suitable bearing assemblies 24. The feed valve preferably comprises a drum 26 secured to shaft 23, and which is provided with a plurality of sets of radially extending flanges, each set of which clamps a flexible valve blade 28 therebetween, of any suitable material such as rubber.

One end of the shaft 23 is connected to suitable driving mechanism in the form of reduction gearing mounted in gear reduction housing 28 supported from a bracket 31 secured to feed valve housing 12; the reducing gearing being driven by a suitable electric motor 32 also supported by bracket 31, and which receives its energy through electrical conductors (not shown) connected to the usual generating mechanism (not shown) on the ship. Preferably, shaft 23 is provided with a detachable bayonet connection 33 with the gearing in gear reduction housing 28, so that the driving mechanism may be readily connected or disconnected for replacement or repair when necessary.

Rotary agitating mechanism is provided in hopper housing 11 adjacent the bottom thereof; such mechanism being for the purpose of minimizing caking of material in the housing, and comprising a plurality of rakes in the form of radially extending rods 34 secured for rotation with a shaft 35. Raking fingers 36 are provided at the outer extremities of rake rods 34.

Shaft 35 is parallel to shaft 23, and projects through and is journalled in opposite walls of hopper housing 11 corresponding to the walls of the feed valve housing 12 in which shaft 23 is journalled; suitable bearing assemblies 37 being provided for journalling shaft 35. The end of shaft 35 adjacent the projecting end of shaft 23 is driven from shaft 23 by a suitable driving connection in the form of a sprocket and chain drive 38. Thus, it is seen that the material is continually agitated in the hopper structure by means of the rake mechanism; and predetermined regulated quantities of the material is fed from the bottom of the hopper structure by means of the feed valve 22. Feeding of the material from the hopper structure may be readily controlled by energization or deenergization of electric motor 32 which is connected to the usual pilot operable control switch 40.

As a further means to insure against caking of the material in the hopper structure, vibrating mechanism is mounted thereon. Such vibrating mechanism comprises a plurality of electric motors 39 which are connected to receive their energy through any suitable electrical conductors 41 connected to the usual generating source of electricity on the ship. The motor shafts are provided with off-balance weights 42 to cause vibration as the shafts rotate. Vibratory motors 78

4

are provided on both the hopper housing as well as the feed valve housing parts of the hopper structure; and by virtue of the fact that the hopper structure is more or less loosely or flexibly held by means of suspension hook 7, efficacious vibration is imparted to the hopper structure.

We claim:

1. Aircraft crop dusting equipment comprising an upright hopper structure adapted to hold dusting material and having a bottom opening for discharge of the material, a generally horizontally extending blast tube communicating with the bottom opening of said hopper structure and which is adapted to receive a blast of air adjacent one end thereof and to discharge said material from the opposite end, and a plurality of vertically spaced generally horizontally positioned baffles in said blast tube positioned with adjacent ends in spaced overlapping relationship, said baffles spanning said bottom opening with a plurality of the spaces between adjacent ends of said baffles underneath said bottom opening.

2. Aircraft crop dusting equipment comprising an upright hopper structure adapted to hold dusting material and having a bottom opening for discharge of the material, a generally horizontally extending blast tube communicating with the bottom opening of said hopper structure and which is adapted to receive a blast of air adjacent one end thereof and to discharge said material from the opposite end, and a plurality of vertically spaced generally horizontally positioned baffles in said blast tube positioned with adjacent ends in spaced overlapping relationship the uppermost baffle being adjacent the blast receiving end of said tube and the lowermost baffle adjacent the discharge end of said tube.

3. The combination with a rotary wing aircraft having an engine cooling fan, of crop dusting equipment mounted on said aircraft comprising an upright hopper structure having a bottom opening for discharge of material from the hopper structure, a generally horizontally extending blast tube communicating with the bottom opening of said hopper structure, one end of said blast tube being connected to an adaptor for receiving a blast of air from said fan, said blast tube being adapted to discharge said material from the opposite end thereof, and a plurality of vertically spaced generally horizontally positioned baffles in said blast tube positioned with adjacent ends in spaced overlapping relationship, said baffles spanning said bottom opening with a plurality of the spaces between adjacent ends of said baffles underneath said bottom opening.

4. Aircraft crop dusting equipment comprising an upright hopper structure adapted to hold dusting material and having a bottom opening for discharge of the material, a single generally horizontally extending blast tube communicating with said bottom opening and which is adapted to receive a blast of air adjacent one end thereof and to discharge said material from the opposite end, and a plurality of generally horizontally positioned baffles arranged longitudinally of said blast tube with adjacent ends thereof in stepped spaced relationship to provide spaces between said adjacent ends, said baffles spanning said bottom opening with a plurality of said spaces between said baffles underneath said bottom opening.
